UNITED STATES PATENT OFFICE.

HENRY ORMOND SCHOOLFIELD, OF MULLINS, SOUTH CAROLINA, ASSIGNOR TO MULLINS LUMBER COMPANY, A CORPORATION OF SOUTH CAROLINA.

HOGSHEAD CLOSURE.

Application filed May 2, 1927. Serial No. 188,283.

The present invention relates to hogsheads or barrels, and particularly to ends, tops or closures therefor.

The invention is particularly adapted, although by no means limited, to use in connection with the relatively large hogsheads employed in the tobacco industry for containing packed tobacco leaves.

It is one of the principal objects of the invention to eliminate the following disadvantage now generally experienced in connection with the hogsheads used for this purpose.

The tobacco leaves, after being picked by the planters and preliminarily dried and cured by them, are taken out of the drying barns and are graded. After grading, it is common custom to convey the graded tobacco to a central warehouse, where the tobacco is sold at auction on the warehouse floor. Here the tobacco is bought by the tobacco dealers, and the partially dried leaves are packed tightly in hogsheads, in which they are shipped to the wholesaler's re-drying plant.

Upon their arrival at the re-drying plant, the hogsheads are turned on end, the lower hoops are cut and removed, which permits the staves to spread at the bottom of the hogshead, making it possible to lift the hogshead off the packed leaves, which, owing to the tightness with which they were packed, have assumed the form of the interior of the hogshead. The tobacco leaves are removed from the head, which at this time is resting on the floor, and are run through suitable drying apparatus, which removes all moisture from the leaves. The used hogshead is knocked down or burned, according to its condition. If it is in good condition, it will, when next used, require a head, to enable the manufacturer to use this hogshead again for packing therein the completely dried and steamed tobacco, in which hogshead the tobacco remains throughout the aging process, which may be a matter of months or years.

It is found, in practice, impracticable to keep separated the assembled parts of the individual heads or end closures of the hogsheads, but the sections of each head become disassembled and mixed with sections of other heads. As these head sections are of different widths and lengths, it is, in practice, impossible readily to locate the necessary sections to assemble into a complete head of cir-

cular form and of the proper size to fit into the end of the re-coopered hogshead.

It is therefore customary to practice in purchasing hogsheads, for the purpose above stated, to purchase at the same time large quantities of board lumber of the same thickness as the head sections, and this lumber is sawed in lengths approximately equal to the diameter of the desired head. A new head for the reassembled hogshead is then laid out and sawed in the following manner:

Enough head sections are laid out in contact to cover approximately the area of the head desired. A section of the cut lumber is inserted somewhere about the middle portion of this assembly, which provides an available head area larger than that required for the desired head, and from this assembly a new head is cut.

It is obvious that this procedure requires a very considerable amount of labor and equipment and involves a very appreciable waste of lumber, the waste including the useless cut-off end lengths of the head sections formerly used, and also including large quantities of new lumber incorporated with the old to produce a new head for the used hogshead.

The principal object of the invention above referred to is to provide a head, end or closure for a hogshead so constructed that neither of the above described wastes need occur.

Other objects and advantages of the invention will appear from the following description, taken in connection with the accompanying drawings, which illustrate the invention in preferred form, but which are not to be taken as a definition of the limits of the invention, reference being had to the appended claim for that purpose.

In the drawings:

Figs. 1 to 3 inclusive are somewhat diagrammatic top plan views of exemplary embodiments of the invention;

Fig. 4 is a similar view illustrating an assembly of head sections for re-sawing in accordance with methods heretofore used and illustrating the lumber saved by the present invention.

Referring in detail to the accompanying drawings, the invention provides a construction of head or end closure which permits of ready, easy and obvious reassembly in such a manner that any head sections, even though each came from a different hogshead, can be

promptly and accurately assembled to form a new head of precisely accurate dimensions and without any sawing, waste or addition of lumber. In Fig. 1 of the drawings, there is illustrated one form of head for accomplishing this purpose. As illustrated, the invention provides, as shown in Fig. 1, a perfectly symmetrical central section, and, on opposite sides thereof, a plurality of sections such that for each section on one side there is an exactly equal section on the other. For example, still referring to Fig. 1, the central section 14 is so constructed that it fits the central part of any hogshead of a given diameter. The section 15 or 16, when added thereto, provides the exact dimensions required for the next piece to be assembled. The sections 15 and 16 are thus identical, and if the workman happens to pick up any two such sections, regardless of the hogsheads from which they came, he is assured that they will provide the necessary fit in the new head which he is assembling. In Fig. 1 the central section is illustrated as being wider than the others. Because of its greater length, and the curvature at its end, this central section can be readily identified. Any such central section can be picked out by the workman from a pile of indiscriminately mixed sections with the assurance that when placed in the center of the head to be assembled, it will be accurate for the head he desires to make without any sawing or other modification. Likewise two sections 15 are readily identifiable by sight, and by turning over one of them, the workman is assured that they will form accurately the necessary sections to be formed on either side of the central section 14. Likewise the sections 17 and 18 are absolutely identical, and because of their decreased width, they are not only easily identifiable so that they may be readily selected by the workman, but because of their identity he can be certain that they will form, when added to the sections already assembled, exactly and precisely the parts required to complete the head which he is assembling. In Fig. 1 the central section 14 is illustrated as being of greater width than the sections 15 and 16, and the outside sections 17 and 18 are illustrated as being of less width than the sections 15 and 16, but it will be evident that all of the sections may be of exactly the same width, and it will also be evident that in constructing a head in accordance with Fig. 1 it is immaterial how many sections are used, provided only that there is a central section and, on either side thereof respectively, a plurality of identical sections.

Referring now to Fig. 2 of the drawings, the head here shown consists of a plurality of sections all of the same width. In this embodiment there are two central sections 20

and 21, which are absolutely identical in all respects, and for practical purposes correspond to the central section 14 in Fig. 1. Of the remaining sections shown in Fig. 2, the sections 23 and 24 are identical and the end sections 27 and 28 are identical.

Referring to Fig. 3, the sections here shown consist of an even number of sections, but of different widths, but it will be observed that the two central sections 32 and 33 are identical; the two sections 34 and 35 are identical, and the two end sections 36 and 37 are identical.

It will be observed that by the foregoing construction of head, any sections of the end closures of any hogsheads or a number of hogsheads may all be reassembled readily, and without going through a process of trial and error, into a plurality of identical heads. The workman knows in advance that any section appearing at all similar to the one for which he is looking will precisely fit the space he desires to fill without sawing or any other modification.

Where, as in present practice, the sections of the heads are all likely to be of different widths, with no two sections of any one head absolutely identical, it is customary to resort to the practice illustrated in Fig. 4, where a central section 40 is provided by an entirely new piece of lumber provided especially for the purpose, and enough sections 41, 42, 43, 44 and 45 are indiscriminately added to this to give the desired area, after which this rough assembly is sawed as indicated by the dotted line 51 to produce a new head. All lumber outside of the dotted circle is wasted, and one entirely new piece of lumber 40 has been utilized.

By the foregoing invention, the use of new lumber and also the waste of old lumber is absolutely avoided.

Various modifications of the invention will occur to those skilled in the art after knowledge of the present disclosure, and it is to be understood that various changes may be made within the scope of the present invention, as defined by the following claim.

What is claimed is:

A circular closure for hogsheads and the like, including two groups of sections, the sections of each individual group differing in shape from the other sections of that group, and there being for every section in one of said groups a corresponding and identically shaped section in the other of said groups, each of said sections being separately inserted in the end of a hogshead to form the head and said sections when assembled forming a disc closure the perimeter of which is a circle.

In testimony whereof I affix my signature.

HENRY ORMOND SCHOOLFIELD.
